UNITED STATES PATENT OFFICE.

WILLIAM T. GUTH, OF BROOKLYN, NEW YORK.

EMBEDDED INKSTAND.

Application filed July 11, 1922, Serial No. 574,155. Renewed March 13, 1925.

This invention relates to ink stands and particularly to an embedded ink stand for use on desks, tables and other desired places and has for an object to provide a construction which will not only require minimum space but which will be out of the way when using the desk.

Another object in view is to provide an embedded ink stand in which removable ink wells may be used.

Another object of the invention is to provide an ink stand having an embedded structure for carrying removable ink wells and for supporting pencils and other articles below the surface of the desk or other support carrying the ink stand.

In the accompanying drawing—

Figure 1 is a perspective view of a table with an ink stand embodying the invention applied thereto.

Figure 2 is a longitudinal vertical section through Figure 1 approximately on line 2—2.

Figure 3 is a transverse sectional view through Figure 1 on line 3—3.

Referring to the accompanying drawings by numeral, 5 indicates a table of any desired kind which is cut out to provide recesses 6 and 7, said recesses merging at one point as indicated in Figure 2 so as to accommodate both the pencil section 8 and the ink well section 9. The stand is provided with a grooved body 10 and in the grooves pencils or other articles may be placed, said body being also provided with a depression 11 for receiving an eraser or other desired article. At the opposite end of the body 10 to the depression 11 is arranged the ink well section 9 positioned above the cut-out portion or cavity 7 in which the ink wells 12 and 13 are positioned. The section 9 is provided with an annular groove or notch 14 which is adapted to receive the frame 15, said frame having openings 16 and 17 designed to be closed by the lids 18 and 19

slidely mounted in grooves formed by the turned in flanges 20 of the frame 15. Each of these lids is provided with a turned up section 21 whereby the lid may be readily slid back and forth to cover or uncover the ink wells arranged therebeneath. This construction adapts itself to a desk, table or the like wherein a number of articles are arranged on the table and are adapted to be shifted from place to place.

It will be noted that an article may be

readily moved over the ink stand without disturbing any of the contents while at the same time the ink stand is ready for use continually. Also, it will be noted that the frame 15 may be bodily removed at any time for removing or re-inserting the ink wells 12 and 13.

What I claim is:—

1. An embedded ink stand and rack formed to be embedded so that at all times no part will be projected above the material in which it is embedded, said ink stand and rack comprising a body having depressions for receiving articles, said depressions being arranged in one part of the body, said body at the opposite end being provided with a large opening, a cover removably fitted into said large opening, said cover having spaced apertures, and a covering plate carried by the frame for each aperture.

2. An embedded ink stand and rack formed to be embedded so that at all times no part will project above the material in which it is embedded, said ink stand and rack comprising a body having an opening adjacent one end, a bodily removable frame arranged in said opening formed with a plurality of apertures and inturned flanges adjacent said apertures, and a sliding cover for each of said apertures, said sliding covers being supported by said flanges and acting to normally close said apertures.

3. An embedded ink stand and rack formed to be embedded so that at all times no part will project above the material in which it is embedded, said ink stand and rack comprising a body having depressions for receiving articles, said depressions being arranged in one part of the body, said body at the opposite end being provided with a large opening, a covering frame fitted into said large opening, said covering frame having spaced apertures arranged therein, and a sliding cover carried by the frame for each aperture.

4. An embedded ink stand and rack formed to be embedded so that at all times no part will project above the material in which it is embedded, said ink stand and rack comprising a frame adapted at one end to cover an ink well and at the other end to receive articles, said article receiving end being formed with a plurality of depressions, said depressions being adapted to receive different articles so that they will be below the surface of the ink stand and rack,

and the end covering the ink well having an aperture, said apertured end being provided with a sliding cover for said aperture whereby said ink well may be covered or exposed 5 at will.

5. An embedded ink stand and rack formed to be embedded so that at all times no part will project above the material in 10 which it is embedded, said ink stand and rack comprising a body formed with a plurality of sockets or depressions for receiving articles, and an aperture for exposing an ink well, a bodily removable covering plate for said aperture, said covering plate having 15 an opening therein, and a shiftable member carried by the covering plate adapted to normally close said opening.

6. An embedded ink stand and rack formed to be embedded so that at all times no part will project above the material in 20 which it is embedded, said ink stand and

rack comprising a body having longitudinally arranged grooves for receiving pencils and the like, a groove at one end for receiving an article, and an opening at the 25 opposite end, a covering frame arranged in said opening provided with an aperture, and a sliding lid for normally closing said aperture.

7. An embedded ink stand and rack 30 formed to be embedded so that at all times no part will project above the material in which it is embedded, said ink stand and rack comprising a body formed with a plurality of grooves for receiving pencils and other articles, an opening at the opposite portion to the portion carrying said grooves, a covering frame arranged in said opening provided with an aperture, and a shiftable 35 lid for normally closing said aperture. 40
